[57] CLAIM

The ornamental design for decalcomania for china dinnerware or similar article, as shown and described.

DESCRIPTION

FIG. 1 is a plan view of my new design for decalcomania for china dinnerware or similar article. The broken line showing of the background surface for the decalcomania is illustrative of environmental structure only and forms no part of the claimed design; and,

FIG. 2 is a plan view of another embodiment of my new design for decalcomania for china dinnerware or similar article.

The broken line showing of the background surface for the decalcomania is illustrative of environmental structure only and forms no part of the claimed design.
